SHOE WITH BACKSTAYS

Fred L. Ayers, Watertown, Mass.

Application April 19, 1950, Serial No. 156,899

22 Claims. (Cl. 36—8.5)

1

This invention relates to shoes and to their manufacture, and has for an object to produce shoes wherein at least portions of both the inner and outersoles are extended upwardly onto the upper at the heel end to form inside and outside backstays.

A further object is to provide for the attachment to the shoe upper of an outside backstay portion which may be an extension at the heel end of the outersole, such attachment being by stitching which is concealed on the inside of the shoe, either by the inside backstay or by the use of stitching which does not pass through the outer but terminates in free marginal portions of an outside backstay member to which an outersole extension may be secured.

Further objects and advantages will appear from a description of constructions shown in the accompanying drawings in which

Figure 1 is a perspective view of a pair of quarters secured together by a back seam and arranged for incorporation in a shoe in accordance with this invention.

Figure 2 is a plan view showing the inside backstay portion of the innersole, top stitched to the quarters of Figure 1.

Figure 3 is a detail sectional view on line 3—3 of Figure 2.

Figure 4 is a view showing the innersole and inside backstay pulled upwardly out of the way and the outside backstay portion of the outersole stitched to the quarters.

Figure 5 is a detail sectional view on line 5—5 of Figure 4.

Figure 6 is a side elevation partly broken away and in section of a shoe constructed in accordance with this invention.

Figures 7 and 8 are detail sectional views on lines 7—7 and 8—8, respectively, of Figure 6.

Figure 9 is a fragmentary view similar to a portion of Figure 4, but showing a modification.

Figure 10 is a heel end view of a shoe incorporating the construction of Figure 9.

Figure 11 is a view generally similar to Figure 6, but including the modifications of Figures 9 and 10.

Figures 12 and 13 are detail sectional views on lines 12—12 and 13—13, respectively, of Figure 11.

Figure 14 is a view similar to Figure 13, but showing the shoe lasted as a welt shoe.

Figure 15 is a fragmentary heel end elevation of a shoe to a larger scale and showing a further modification.

Referring to Figures 1, 2, and 4, at 1 is shown

5 the laminated quarters of a shoe upper which are secured together by a back seam at 2 as shown in Figure 1. These quarters are also provided with a combined top and eyelet stays 3. To the quarters thus secured together, is secured by the top stitching as at 4 (see Figure 2), the upper end of a combined or integral inside backstay and innersole 5. The remainder of the integral inside backstay and innersole is left unattached for the time being and is pulled upwardly, and a combined or integral outersole and outside backstay 6 is secured at its backstay portion to the quarters as by stitching 7 as shown in Figure 4. This stitching passes through the quarters but somewhat within the margin of the inside backstay portion of the member 5 so that thereafter when this backstay portion is replaced and cemented against the inner faces of the quarters, it hides the stitches which secure the outside backstay in position. In Figures 4 and 5, the member 5 is shown as pulled out of the way, permitting the attachment of the outside backstay portion of the member 6 without the stitches passing through the inside backstay where they would be visible on the inner face of the completed shoe. This provides a smooth interior surface of the shoe for presentation to the foot and also conceals any manufacturing inaccuracies in relative positioning of the inside and outside backstay portions, which, if the stitching appeared on the inside of the shoe, would show the stitching unsymmetrically positioned with respect to the inside backstay.

35 After the innersole and outersole members 5 and 6, respectively, have been secured to the quarters, the shoemaking proceeds as desired. For example, the margins of the innersole member 5 at the innersole portion may be secured to the lower margins of the quarters and the shoe may then be slip lasted, after which the outersole portion of the member 6 may be attached thereto to form a shoe of the stitch-down type as illustrated in Figure 13. If desired, also, counter stiffening means may be employed. As shown for example, in dotted lines in Figures 1 and 2 and in full lines in Figures 4 and 6, external stiffening patches 10 may be employed which have their adjacent edges located between the inside and outside backstay portions. These patches may be in the form of pockets for receiving separate stiffening elements, or their inner faces may be coated with a liquid stiffening agent before they are assembled in the shoe, which, when allowed or caused to harden, produces the desired stiffness. Instead of lasting

55

the shoe in accordance with the slip lasting or stitch-down methods, it may be otherwise lasted, as by the welt method as shown in Figure 14, a stitch-receiving rib 11 of any suitable description having been secured to the lower face of the innersole member 5 about the innersole portion, or the shoe may be cement lasted, if desired, as shown for example, in Figure 8 where the lower margins of the upper materials are cemented to the under face of the innersole 5.

By using the continuous inside backstay and innersole, a smooth rounded contour is formed within the shoe for engagement with the foot in accordance with the disclosure of my Patent No. 2,460,699 granted February 1, 1949.

The use of the combined outersole and outside backstay provides for a smooth uninterrupted face for the shoe sole and rear end. However, in some cases it may be desired to employ a separate outside backstay with an outersole having an outside backstay portion.

As shown in Figure 9, a backstay 15 separate from the outersole may be secured in position by the stitching 16, the innersole being held out of the way while the stitching is being placed, so that when the inside backstay is replaced it will cover the line of stitching. After the outside backstay 15 has been so placed, leaving marginal unsecured portions 17 outwardly of the securing stitching, a combined outersole and outside backstay portion similar to that shown in Figures 4 and 5 at 6 may be applied, being secured to the innersole and such other parts as may be desired by a continuous line of stitching 20, which at the outside backstay 15, is secured to this outside backstay at the free margin 17. Thus a continuous line of stitching secures the combined outersole and outside backstay, but the stitching at the outside backstay portion being positioned at the free margins of the outsole backstay 15 does not pass through the upper and hence is not visible from the inside of the shoe. This is shown, for example, in Figure 12.

In Figure 15 a modification is shown in which the outersole 6a has a relatively short rearward extension 21 which may be turned up against the outer face of the upper either with or without an outside backstay member interposed therebe-

tween, this portion 21 being secured to the upper materials as by the line of stitching 22. This line of stitching may be placed before the inside backstay is replaced after being attached by the top stitching to the quarters so that when this inside backstay is replaced it covers the line of stitching 22. If desired, of course, this line of stitching 22 could be placed after the inside backstay 5 is in position, whereupon it would show on the inside of the shoe.

From the foregoing description of certain embodiments of this invention it will be evident to those skilled in the art that various further changes and modifications may be made without departing from the spirit or scope of this invention.

I claim:

1. A shoe having laminated quarters stitched together at their top edges, an outsole having a backstay stitched to said quarters at its top and sides, and an insole having integral therewith a backstay stitched to said quarters by said top stitching only and cemented to the inner face of said quarters and covering the stitches which secure the sides of said outsole backstay to said quarters.

2. A shoe having laminated quarters stitched together at their top edges, an outsole having a backstay integral therewith stitched to said quarters at its top and sides, and an insole having integral therewith a backstay stitched to said quarters by said top stitching only and cemented to the inner face of said quarters and covering the stitches which secure the sides of said outsole backstay to said quarters.

FRED L. AYERS.
